UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed June 12, 1920. Serial No. 388,453.

To all whom it may concern:

Be it known that I, BURNHAM C. STICKNEY, a citizen of the United States, residing in Elizabeth, in the county of Union and 5 State of New Jersey, have invented certain new and useful Improvements in Typewriting Machines, of which the following is a specification.

The present invention relates to paper- 10 feeding and controlling devices in such typewriting machines as have sets of pressure-rolls, one set arranged in advance of the other in line-feed direction on the platen, and between which rolls and the platen the 15 work-sheets are gripped and fed. More particularly, the invention relates to mechanism for effecting in such a machine an initial positioning with respect to one another of a plurality of work-sheets superposed on the 20 platen; as, for instance, when such superposed sheets are of different character; but, through the medium of interleaved carbons, are to have the same matter typewritten thereon at different distances from the top 25 edge of a sheet.

It is desirable, for instance, to make an entry on a ledger-sheet in the same operation in which an individual statement is typewritten. Owing, however, to the fact 30 that the headings or top margins are ordinarily different on the ledger and statement-sheets, or that one sheet may already have writings thereon, the point at which the new matter is to be written may not be 35 at the same distance from the leading edges of the two sheets; and so, if, as is most convenient, the leading edges are brought together for insertion of the sheets as a unit into the machine, then when the top sheet 40 is in writing position, the other sheet may have been fed too far or not far enough, and adjustment is required, if the matter to be written is to appear at the proper places on both sheets.

45 Heretofore in machines which have sets of feed-rolls, arranged one set in advance of the other in line-feed direction on the platen, the structure has been such as to require disengagement of the top sheet by those rolls 50 normally in engagement therewith, and the use of special means for retention of the

top sheet after the same is positioned and before the ledger or other under sheet is adjusted relatively thereto.

An object of the present invention is, in 55 a machine of the character described, to obviate the necessity for disengagement of the feed-rolls from the top sheet, and furthermore to use such rolls as means for holding the position of the top sheet, to permit of 60 adjustment of the under sheet relatively thereto. To this end, in a machine in which independently-revolvble feed-rolls are spaced across the work-sheets between the 65 ends of the platen, I use a top sheet narrower than the under sheet, or insert the sheets into the machine in such manner that the under sheet extends laterally beyond the top sheet, thus allowing the under sheet to be gripped by certain of the pressure-rolls which do not 70 touch the top sheet.

I provide means for locking at will against free rotation, preferably by brakes, those 75 rolls which normally bear on the top sheet, so that such rolls when locked will offer a frictional resistance to the movement thereover of the top sheet, and will hold the latter in the line position to which the several sheets may have been inserted. Preferably, in one operation with such locking of 80 the rolls, and by virtue of applying the brake pressure counter to the original pressure of the rolls on the platen, I relieve the locked rolls of sufficient of their normal pressure on the platen to make certain that 85 they will not be turned by the platen and to permit of such easy movement of the under sheet with the platen and unlocked rolls that smudging of the under sheet by the interleaved carbon will not occur. The counter pressure of the brakes may slightly move 90 the rolls to which they apply from the platen, but such movement when present should not be sufficient to cause the rolls to release the top sheet, and ordinarily would 95 not be discernible.

100 Preferably, to hold the top sheet while the under sheet is adjusted, I render non-revolvble all the rolls which have contact therewith. It will often be sufficient, however, if certain only of the rolls on the top sheet are locked. If other rolls on the top sheet are

not locked against rotation, the normal pressure thereof should nevertheless be so relieved as to prevent the same from pulling or pushing the top sheet when the platen moves with the under sheet.

5 Other features and advantages will hereinafter appear.

In the accompanying drawings,

10 Figure 1 is a front view, showing my invention applied to a platen-frame of the character used in the Remington typewriting machine.

Figure 2 is a rear view of the devices shown in Figure 1.

15 Figure 3 is a view in cross-section, taken on the line 3—3 of Figure 2, the parts being shown in normal, or writing, position.

20 Figure 4 is a view similar to that of Figure 3, the parts being in position for line-feed of the ledger-sheet relative to the statement-sheet.

Figure 5 is a perspective view of the platen-frame and attached parts, looking down from the left rear corner.

25 Figure 6 is detail view, showing one of the brake-units and its actuating carrier in their relation to one front and one rear feed-roll.

30 The platen 10, of the usual cylindrical type, is carried by an axle 12, journaled in end frames 13 and 14, which are connected by cross-bars 15 and 16. Finger-wheels 17 and 18 for actuating the platen 10 are provided on the ends of axle 12, and suitable line-spacing mechanism may be provided.

35 A shaft 19 at the rear of the platen is carried by angular brackets 20 which are journaled at the ends of their upright arms on a shaft 21, supported in the end frames 13 and 14, and which have forward extensions secured to cross-bar 15. Mounted on shaft 19 are three-arm levers 22, six in number, the forward arms 23 of which are pivoted at 24 to carriers or yoke-pieces 25 at points intermediate of their ends. The yoke-pieces 25 extend transversely of the platen and beneath the same, and are provided at their ends with shafts 26 and 27, carrying forward feed-rollers 28 and rear feed-rollers 29, respectively. In order to hold the feed-rollers 28 and 29 in effective position, relative to the platen, helical springs 30 are connected to cross-bar 15 at one end, and, by means of screws 30^a, to depending arms 31 of the three-arm levers 22. It will be seen that engagement of the screws 30^a in the coils of the helical springs 30 enables adjustment of the tension of the springs. Due to the use of the yoke-pieces 25 the pressure exerted by the springs 30 will be distributed between the forward and rearward sets of rollers.

60 The shafts 26 and 27, opposite the central portion of the platen 10, are of greater

length than the other shafts 26 and 27, and each of these central shafts 26 and 27 carries three rolls. Only one roll is supported on each of the other shafts 26 and 27.

65 In order to control the position of the three-arm levers 22 and the effectiveness of the feed-rolls, shaft 21 is provided with a finger-piece 32 and with arms 33, secured fixedly thereon. Upon rotation of shaft 21 by the finger-piece 32, the arms 33 will actuate the corresponding upwardly extending arms 34 of the three-arm levers 22, and cause withdrawal of the carriers or yoke-pieces 25, and consequently of the feed-rollers 28 and 29 from effective position with respect to the platen.

70 It will be noted that the pivots at 24 are situated to the rear of the middle points of yoke-pieces 25. As a consequence of this arrangement, the forward rolls 28 are withdrawn from the platen before the rear rolls 29; and, in order to insure withdrawal of said rear feed-rolls, resilient members 37 are secured on cross-bar 15 in position to co-operate with the forward feed-roller shafts 26. As seen in Figure 1, each of the end members 37 serves to act as a stop-support for one end of a shaft 26, while each of the intermediate members 37 acts similarly on the ends of two of said shafts and is forked to better adapt it for that purpose. Obviously, each of the members 37 may be replaced by two single members.

75 A paper-table 38 is pivoted at 39 to forwardly-extending arms 40 of bell-crank pivoted on shaft 19 and having depending arms 41 connected by springs 42 to the cross-bar 15. It will be seen that the springs 42 tend to maintain the paper-table in position to co-operate with the platen. At the rear, the paper-table rests floatingly against certain of the parts supported on shaft 21. The depending arms 41 are provided with lugs 43 extending to the rear of the outside depending arms 31, so that withdrawal of the outer feed-rollers will effect withdrawal 80 of the paper-table.

85 Upon movement of finger-piece 32 to its extreme rearward position, the feed-rollers and the paper-table will be moved away from the platen to permit the insertion of the work, which, in this case, comprises a statement-sheet A opposite the central rollers, and a ledger-sheet B having its margins extending beyond the margins of the statement-sheet and in position to be engaged by the outer rollers, a carbon-sheet C being interleaved between the work-sheets. Upon release of the finger-piece 32, the feed rollers and paper-table will be returned to their 90 normal positions.

95 When the work-sheets are placed in cooperative position with the platen as just described, the lines along which typewriting

is to be done may be at different heights upon the sheets. It will then be necessary to effect a relative adjustment of the sheets. To this end, provision is made for holding the statement-sheet against movement while the ledger-sheet is fed by the platen.

Since the statement-sheet is the sheet against which the three central of the front and back feed-rolls directly bear, such central feed-rolls may, as stated, conveniently be employed as the means for holding the statement-sheet against line-feed movement while the ledger-sheet is given a line-feed movement by rotation of the platen. As hereinbefore stated, the central feed-rolls may have this function if at the proper time they are prevented from rotating with the platen and end feed-rolls; for, if the feed-rolls are of rubber or other suitable material, they will prevent slipping thereover of the statement-sheet with which they are in contact, while the smooth back of the carbon-sheet will offer little or no resistance to line-feed movement of the ledger-sheet. This is on the assumption that the pressure of the feed-rolls on the platen, as by means of the springs 30, is not too great. To utilize the central feed-rolls as holding devices for the statement-sheet while the ledger-sheet is brought to proper line-position, I therefore, in the preferred embodiment of the invention, herein illustrated, employ brakes applied directly to the feed-rolls, and at the same time relieve the pressure of the springs 30.

In the drawings, both ends of the middle front and rear feed-rolls, and the opposing ends of the rolls next thereto on either side, are shown as cylindrical extensions 50 of less diameter than the rolls proper, and form braking surfaces of suitable frictional material. These brake surfaces may be integral with, and of the same material as, the rolls proper, or may be sleeves on which the rolls are carried, and may be of different material from the rolls. The brake-shoes 51, shaped to the curvature of the brake surfaces on the rolls, are conveniently mounted in two units of four shoes each. The shoe 51 for the left-hand brake surface of the central rear feed-roll and the shoe 51 for the brake surface of the rear feed-roll next adjacent to the left of the centre are carried on arms 52 which form a yoke integral with and carried by a centre piece 53 (see Figure 6). Similarly, the brake-shoes for the left-hand brake surface of the front centre feed-roll and for the front feed-roll next to the left of the centre are carried on arms 54 also integral with the centre piece 53. This double yoke thus formed is pivotally and somewhat loosely supported on a cross pin 55 carried in aligned bearings in hubs 56 on the arms 57 of a fork 58 pivoted on the rock-shaft 19. Collars 59 se-

cured to shaft 19, as by means of set screws 59^a, hold the fork 58 from displacement longitudinally of the shaft. A similarly constructed double yoke carries the brake-shoes for the right-hand brake surfaces of the centre front and rear feed-rolls, and for the brake surfaces of the front and rear feed-rolls immediately to the right of the centre rolls; and, like the other double yoke, is carried on the rock-shaft 19 by a forked carrier 58. Each of the forks 58 has integral therewith, and forms a bell crank with, an upwardly-extending arm or dog 60. The carriers 53 being pivoted loosely at 55, and the forks 58 being pivoted on the shaft 19, the brake-shoes settle by gravity on the brake surfaces of the rolls; but the weight thereof is not sufficient normally to interfere with the rotation of the rolls with the platen or to affect the pressure of the rolls on the platen, due to the strength of the springs 30. The arms 60 are adapted to be engaged and rocked by arms 61 fast on a rock-shaft 62 carried in the frame members 13 and 14. Also fast to the rock-shaft 62 is an operating lever 63 which may have a finger-piece 64. A coil spring 65 embracing the shaft 62, and attached at one end to the left-hand frame piece 13 and at the other end bearing against or attached to the lever 63, may be employed to maintain the normal position of the arms 61, shaft 62 and lever 63, and to return the same to normal position after an operation thereof. A plate 66 fixed on the cross-bar 16 has two stop pins 67 and 68 which serve to determine respectively the normal position and the extreme throw of the arm or lever 63. A spring detent 69, secured to the arm 62, may engage with either of two pockets 70 and 71 in the face of the plate 66; the pocket 70 to hold the lever 63 against accidental displacement from normal position, and the pocket 71 to hold the lever in its effective position; in which case the spring 65 may or may not be employed.

Normally, and except when the statement and ledger sheets are being moved relatively to each other, the parts are in Figure 3 position, the lever 63 being in its forward position and the brake-shoes 51 being ineffective on the feed-rolls which engage the statement-sheet. When the sheets are to be inserted in the machine, the lever 32 is preferably first thrown back to remove the feed-rolls and paper-table 38 from the platen. As the brake-carriers 53 rest on the feed-rolls, these follow the rolls when lever 32 is operated. With the parts in this position, the statement and ledger sheets, with the interleaved carbon and any proof-sheets, are inserted together into the machine until the statement-sheet has been brought to printing position. The lever 32 and pressure rolls are then returned to nor-

mal position. At this time all the feed-rolls are effective on the ledger-sheet, but, by reason of the lesser width of the statement-sheet, the extreme right and left rolls do not bear on the latter. The lever 63 is now thrown back, (by hand pressure in the embodiment of the invention shown), thus rocking the shaft 62 to cause the arms 61 thereon to engage and press forward the arms 60 which are integral with the forks 58 on the shaft 19, and which cause these forks to be depressed, and the brake-carrying yokes, attached thereto, to be tightened down until the brakes are effective on the feed-rolls. Due to the double yokes by which the brake-shoes 51 are carried, the pressure exerted through the forks 58 will be distributed between the front and rear brake-shoes.

It will be noted that the direction of application of the brakes is away from the platen; that is to say, the pressure of the brakes is opposed to the pressure exerted by the springs 30. The normal tension of the springs 30 is such that the feed-rolls would tend to turn and might actually turn with the platen despite the brake action, unless the normal pressure of the rolls on the platen is relieved to some extent; and, again, if the rolls were held against the platen by the full and unrelieved tension of the springs 30, while nevertheless held against rotation by the brakes, then smudging of the ledger-sheet by the carbon C might occur when relative movement of ledger and statement sheets took place. The pressure of the brakes on the feed-rolls in a direction away from the platen, and in opposition to the pressure of the springs 30, should therefore be appreciable, while yet not so great as to render uncertain a contact of the rolls with the statement-sheet sufficient to hold the latter when the ledger-sheet is moved by the platen. The brake pressure may result in a slight bodily movement of the feed-rolls, but such movement would ordinarily be indiscernible except in so far as indicated by ease of movement of the ledger-sheet relative to the statement-sheet.

When the arm 63 is thus thrown rearward, the extreme right and left feed-rolls continue to exert their normal pressure on the margins of the ledger-sheet and thus insure line-feed of the latter with the platen to bring the ledger-sheet to position for writing the matter for which the statement-sheet has been previously positioned.

Upon release or forward movement of the lever 63 to normal position, the pressure of the brakes is relieved and the full effort of those springs 30 which have been relieved by the brake action becomes again effective for line-feed of the statement-sheet with the ledger-sheet.

Variations may be resorted to within the scope of the invention, and portions of the improvements may be used without others.

Having thus described my invention, I claim:

1. In a typewriting machine, in combination with a platen; a plurality of feed-rolls, one forward of the other in line-space direction on the platen; means for effecting pressure of the feed-rolls on the platen so that work-sheets may be gripped and fed between the rolls and platen; and braking means for exerting balanced pressure on said rolls to hold them against rotation and thereby cause the same to hold stationary such work-sheet as may be in contact therewith, while permitting movement of the platen relative thereto.

2. In a typewriting machine, in combination with a platen; a plurality of feed-rolls, one forward of the other in line-space direction on the platen; means for effecting a pressure of the feed-rolls on the platen so that work-sheets may be gripped and fed between the rolls and platen; and means for locking the rolls against rotation to cause the same to hold stationary such work-sheet as may be in contact therewith, and for relaxing the pressure of the feed-rolls on the platen during the time the rolls are thus locked so that the platen may then have movement relative to such work-sheet as is engaged by the rolls.

3. In a typewriting machine, in combination with a platen; a plurality of feed-rolls, one forward of the other in line-space direction on the platen; means for effecting a pressure of the feed-rolls on the platen so that work-sheets may be gripped and fed between the rolls and platen; and brakes applicable to the rolls, from a direction opposed to the feed pressure, to diminish the latter, and concomitantly to hold the rolls against rotation, so that a work-sheet in contact with the rolls may thereby be held stationary and the platen moved with respect thereto.

4. In a typewriting machine, in combination with a platen; a plurality of sets of pressure feed-rolls for engagement with work-sheets of less width than the platen, one set being located forward of the other set in line-space direction; other pressure feed-rolls co-operating with the platen for engaging wider work-sheets at points beyond the margins of the sheets engaged by the first-mentioned or more centrally-disposed feed-rolls; and means for relieving the pressure of the several sets of more centrally-disposed feed-rolls and for locking the same against rotation, so that a narrower work-sheet in contact with the locked rolls may thereby be held stationary while the platen with a wider work-sheet is moved relatively thereto.

5. In a typewriting machine, in combination with a platen; a plurality of sets of pressure feed-rolls for engagement with work-sheets of less width than the platen, one set being located forward of the other set in line-space direction; other pressure feed-rolls co-operating with the platen for engaging wider work-sheets at points beyond the margins of the sheets engaged by 70
 5
 10 the first-mentioned or more centrally-disposed feed-rolls; and brakes applicable to the several sets of more centrally-disposed feed-rolls to lock the same against rotation, the pressure of the brakes being counter to 75
 15 the normal pressure of the rolls to diminish such normal pressure when the rolls are locked, so that a narrower work-sheet in contact with the locked rolls may thereby be held stationary while the platen is moved
 20 to adjust a wider work-sheet with respect thereto.
6. In a typewriting machine, in combination with a platen; pressure feed-rolls arranged on several axes parallel to the axis 80
 25 of the platen and spaced, one forward of the other in line-space direction; pressure-controlling means for said rolls whereby a change of pressure on one will cause a change of pressure on the others; a brake-device co-operating with both the forward and rearward rolls to lock the same against rotation and constructed so as to distribute the braking action on the rolls; and means for actuating the brake-device.
- 30 7. In a typewriting machine having a revolute platen and having spring-pressed feed-rolls to run upon the platen, the rolls being spaced from each other around the platen, the combination with a finger-piece, 85
 35 of means operable thereby to relax the pressure of all rolls and concomitantly apply frictional opposition to the rotation of said rolls, whereby said rolls are enabled to co-operate to retain a work-sheet against displacement while another work-sheet is shifted around the platen between the same and the first work-sheet.
- 40 8. In a typewriting machine having a revolute platen and having spring-pressed feed-rolls to run upon the platen, the rolls being spaced from each other around the platen, the combination with a finger-piece, 90
 45 of means including individual brakes for said rolls and connected to said finger-piece to be operated thereby, for simultaneously relaxing the pressure of said rolls against a work-sheet and braking the rolls, whereby said rolls are enabled to retain the work-sheet against displacement while another work-sheet is shifted around the platen between the same and the first work-sheet.
- 50 9. In a typewriting machine, in combination with a platen; pressure feed-rolls arranged on several axes parallel to the axis 95
 55 of the platen and spaced one forward of the other in line-space direction; a device having an arm extending forward with a brake-shoe thereon for co-operation with the forward feed-roll and an arm extending rearward with a brake-shoe thereon for co-operation with the rearward feed-roll; a lever carrying said brake-device; and means for operating the lever to apply the brakes to the feed-rolls.
10. In a typewriting machine, in combination with a platen; pressure feed-rolls arranged on several axes parallel to the axis of the platen and spaced one forward of the other in line-space direction; a yoke or forked device, the several arms of which 100
 105 carry brake-shoes for engagement with aligned feed-rolls on the forward axis and other brake-shoes for aligned feed-rolls on the rearward axis; and means for applying the brakes to prevent rotation of the rolls.
11. In a typewriting machine, the combination with a platen, of a plurality of sets of pressure feed-rolls for engagement with work-sheets of less width than the platen, one set being located forward of the other set in line-space direction; other pressure feed-rolls co-operating with the platen for engaging wider work-sheets to one side of the margins of the sheets engaged by the first-mentioned feed-rolls, and means for 110
 115 relieving the pressure of the several sets of first-mentioned feed-rolls and for locking the same against rotation, so that a narrower work-sheet in contact with the locked rolls may thereby be held stationary while the platen with a wider sheet is moved relatively thereto.
12. In a typewriting machine having a revolute platen, a plurality of feed-rolls spaced from each other around the platen, yielding means for pressing said feed-rolls toward the platen with balanced pressures, and means for applying balanced forces to the feed-rolls in opposition to the pressing means to reduce the pressure of the rolls against the work, and for preventing rotation of the rolls.
13. In a typewriting machine having a revolute platen, a plurality of feed-rolls spaced from each other around the platen, means for pressing the feed-rolls toward the platen comprising adjustable spring means and connections for distributively transmitting the force of the spring means to the feed-rolls in a definite ratio, and braking means movable a predetermined distance, arranged to exert balanced forces upon the front and rear feed-rolls, to reduce the pressure thereof against the platen and to prevent rotation of the rolls.
14. In a typewriting machine, in combination with a platen; a set of feed-rolls spaced one from the other between the working margins of the platen; a second set of feed-rolls removed from said first rolls in line- 120
 125
 130

feed direction and also spaced one from the other between the margins of the platen; parts fast to certain of the more centrally located of the rolls of both sets and having 5 brake surfaces thereon; brake-shoes between the platen and the brake surfaces of the rolls so as concomitantly to brake the rolls and relieve their pressure on the platen; and means for applying the brakes to relieve 10 their pressure and to hold such braked rolls against rotation while the unbraked rolls rotate with movement of the platen.

15. In a typewriting machine, in combination with a platen; a set of feed-rolls spaced one from the other between the working margins of the platen; a second set of feed-rolls removed from said first rolls in line-feed direction and also spaced one from the other between the margins of the platen; 20 parts fast to certain of the more centrally located of the rolls of both sets and having brake surfaces thereon; brake-shoes between the platen and the brake surfaces of the rolls; and means for applying the brakes to hold such braked rolls against rotation while the unbraked rolls rotate with movement of the platen, the brake pressure being counter to the normal pressure of the rolls on the platen to relieve such normal pressure to an extent suitable for the movement 30 of the platen relative to the braked rolls.

16. In a typewriting machine, in combination with a platen; a set of feed-rolls spaced one from the other between the working margins of the platen; a second set of feed-rolls removed from said first rolls in line-feed direction and also spaced one from the other between the margins of the platen; parts fast to certain of the more centrally 40 located of the rolls of both sets and having brake surfaces thereon; a carrier having four brake-shoes thereon, one shoe each for the opposing ends of adjacent rolls in one set, and one shoe each for the opposing ends 45 of adjacent rolls in the other set; and means connected to the carrier for applying brake pressure to the rolls affected thereby, to prevent rotation thereof while other of the feed-rolls remain free to rotate with movement 50 of the platen.

17. In a typewriting machine, in combination with a platen; a set of feed-rolls spaced one from the other between the working margins of the platen; a second set of feed-rolls 55 removed from said first rolls in line-feed direction and also spaced one from the other between the margins of the platen; parts fast to certain of the more centrally located of the rolls of both sets and having brake 60 surfaces thereon; a carrier having four brake-shoes thereon between the platen and brake surfaces of the rolls, one shoe each for the opposing ends of adjacent rolls in one set, and one shoe each for the opposing ends

of adjacent rolls in the other set; and means 65 connected to the carrier for applying brake pressure to the rolls affected thereby, counter to the normal pressure of the rolls, to prevent rotation thereof while other of the feed-rolls 70 remain free to rotate with movement of the platen.

18. In a typewriting machine, in combination with a platen; a set of feed-rolls spaced one from the other between the working margins 75 of the platen; a second set of feed-rolls removed from said first rolls in line-feed direction and also spaced one from the other between the margins of the platen; parts fast to certain of the more centrally located of the rolls of both sets and having 80 brake surfaces thereon; two carriers, each having brake-shoes thereon to engage certain of said braking surfaces in both sets; a pressure arm for each carrier; a shaft on which said pressure arms are fast; and a lever on said shaft for rocking the same to apply the brake pressure.

19. In a typewriting machine, in combination with a platen; a set of feed-rolls spaced one from the other between the working 90 margins of the platen; a second set of feed-rolls removed from said first rolls in line-feed direction and also spaced one from the other between the margins of the platen; parts fast to certain of the more centrally 95 located of the rolls of both sets and having brake surfaces thereon; brake-shoes between the platen and the brake surfaces of the rolls; means for applying the brakes to hold such braked rolls against rotation while the unbraked rolls rotate with movement of the platen; and means for throwing the rolls from the platen for insertion of work-sheets.

20. In a typewriting machine, in combination with a platen; a set of feed-rolls spaced one from the other between the working margins of the platen; a second set of feed-rolls removed from said first rolls in line-feed direction and also spaced one from the other between the margins of the platen; parts fast to certain of the more centrally located of the rolls of both sets and having brake surfaces thereon; brake-shoes between the platen and the brake surfaces of the rolls; means for applying the brakes to hold such braked rolls against rotation while the unbraked rolls rotate with movement of the platen; and means for throwing the rolls and brakes from the platen for insertion of work-sheets.

21. In a typewriting machine, in combination with a platen; a set of feed-rolls spaced one from the other between the working margins of the platen; a second set of feed-rolls removed from said first rolls in line-feed direction and also spaced one from the other between the margins of the platen; a paper-table having apertures therein for the feed-rolls; parts fast to certain of the 125

more centrally located of the rolls of both sets and having brake surfaces thereon; brake-shoes between the platen and the brake surfaces of the rolls; means for applying the brakes to hold such braked rolls against rotation while the unbraked rolls rotate with movement of the platen; and means for

throwing the rolls and paper-table from the platen for insertion of work-sheets.
